UNITED STATES PATENT OFFICE

COWPER S. HAMMOND, OF ST. LOUIS, MISSOURI

SHEET METAL ROOFING

Application filed March 5, 1930. Serial No. 433,194.

This invention relates to sheet metal roofing, and has special reference to improvements in lap-joints for sheet metal roofing, whereby the passage through the joints of 5 water, snow and other substances is prevented.

An object of the invention is to provide an improved lap-joint for sheet metal roofing, in which the marginal portion of each of the 10 sheet metal sections that is overlapped by the marginal portion of an adjacent section is corrugated to provide a drain groove between upwardly rounded corrugations, and in which a flat portion of the adjacent section 15 spans and bridges said groove and seats upon the upper corrugations at the sides of said groove and forms therewith closed joints substantially preventing the passage of water and other substances into said spanned 20 and bridged groove. To obtain this object, that portion of each sheet metal section overlapping the drain groove in the adjacent section has its edge curved downwardly to correspond with and fit against the correspondingly curved corrugations of the latter section, while the flat overlapping portion of each sheet metal section extends straight across between the upper surfaces of the two 25 corrugations forming the covered drain groove, so as to cover and leave said drain groove unobstructed. The overlapping portions of the sheet metal roof sections are pierced by nails passing through them in a 30 relationship in which the nails pass through the upwardly curved corrugations of the undersection, thus forming nail holes above the 35 bottom of the drain groove only.

By this improved construction, I provide 40 an imperforate covered drain groove having approximately the same unobstructed depth as the depth of the remaining corrugations of the sheet metal sections, and it is nearly impossible for water and other substances to 45 enter the drain groove to cause the close contact of the upper section with the upper surfaces of the corrugations at the sides of the drain groove.

Other objects of the invention will appear 50 from the following description, reference be-

ing made to the accompanying drawing, in which—

Fig. 1 is a cross-sectional view showing my improved lap-joint construction.

Fig. 2 is a perspective view.

All of the sheet metal sections are of duplicate construction, each being longitudinally corrugated to provide a downwardly extended marginal portion 1 having its edge in the same plane as the lower surfaces of the downwardly curved corrugations 2. Thus, the corrugations 2 and the edge of the marginal portion 1 bear against the roof supporting members 3.

All of the corrugations from the marginal portion 1 to the corrugation 4 are alike as to width and depth. From the corrugation 4, each sheet metal section is extended to provide a flat portion 5 terminating in a downwardly curved edge 6 corresponding to the curvature of the corrugations.

The width of the flat portion 5 is equal to the distance between the crests of the two adjacent corrugations 7 and 8, which are the first two corrugations inwardly from the marginal portion 1 of each sheet. The flat portion 5 thus spans and bridges the groove 9 formed by the corrugation of the sheet metal between the corrugations 7 and 8. This covers the groove 9 and leaves said groove unobstructed for the free discharge of water.

The sheet metal sections are assembled to form a roof by arranging them in a relationship in which the flat portions 5 overlap the corrugations 7 and 8 of adjacent sections to cover and leave unobstructed the drain grooves 9. The downwardly curved marginal edges 6 seat closely against the corrugations 8, and the flat portions 5 seat closely upon the crests of both corrugations 7 and 8 of the respective sheets; while the downwardly curved portions 10 of the corrugations 4 seat closely against the curved edges 1. The flat portions 5 and the crests of the corrugations 7 and 8 may be provided with 90 registering holes 11 through which nails 12 may be driven. Thus, these nails 12 are at the crests of the corrugations 7 and 8 and leave unobstructed and imperforate the channels 9.

These sheet metal sections for a sheet metal roof of the lap-joint type may be manufactured in large quantities at comparatively low cost and expense, because they are of duplicate construction. There is no difficulty in assembling the sections to provide a roof, since the fitting of the parts 5, 6 and 10 of each section upon the corrugations 7 and 8 of an adjacent section will necessarily arrange the sections in their proper relationship. The holes 11 may be provided in either one or both overlapping portions, or these holes may be omitted if desired.

It is now apparent that my invention obtains its intended objects and purposes in an efficient and economical manner.

What I claim is:—

1. A sheet metal roofing section having a plurality of uniform corrugations parallel with and covering the entire area between the longitudinal edges of said section and having one edge extending downwardly and terminating in approximately the same plane with the under sides of the lowest portions of all of said corrugations and having adjacent to and parallel with its opposite edge a flat portion of a width equal to the distance between the crests of any two of said corrugations, the marginal edge of said flat portion being curved downwardly according to the downward curvature of said corrugations, said flat portion being adapted to seat upon and span any two corrugations of an adjacent roofing section in a relationship in which the curved portions adjacent to said flat portion engage closely the curved portions of the corrugations of the adjacent sheet.
2. A sheet metal roof comprising corrugated metallic sections each having a continuous series of uniform corrugations parallel with its longitudinal edges and covering the entire area between one longitudinal edge and a line spaced from the opposite longitudinal edge a distance approximately equal to the width of two of such corrugations and each having a flat portion between said line and the adjacent edge, a downwardly curved margin along the edge of said flat portion, said flat portion overlapping and seating upon two corrugations of an adjacent section and said curved marginal edge lying closely against the surface of one of said corrugations of said adjacent section, there being an unobstructed drain channel under said flat portion, and fasteners passing through said flat portion and through the crests of both corrugations upon which said flat portion is seated and into the support upon which the roof is mounted.
